Primary Examiner — Ian Simmons*Assistant Examiner* — Samantha Q Lawrence*(74) Attorney, Agent, or Firm* — RatnerPrestia**(57) CLAIM**

The ornamental design for a wheel for a motor vehicle, as shown and described.

DESCRIPTION

FIG. 1 is a perspective view of a wheel for a motor vehicle; FIG. 2 is a side elevation view of the wheel; and, FIG. 3 is a front elevation view of the wheel.

The broken line areas show portions of the wheel for motor vehicle that form no part of the claimed design.
